UNITED STATES PATENT OFFICE.

JOSEPH J. WALSER, OF CHICAGO, ILLINOIS, ASSIGNOR TO THE GOSS PRINTING PRESS COMPANY, OF CHICAGO, ILLINOIS, A CORPORATION OF ILLINOIS.

ROTARY FOLDING MECHANISM FOR PRINTING-PRESSES.

No. 926,223.

Specification of Letters Patent.

Patented June 29, 1909.

Application filed March 30, 1908. Serial No. 424,175.

To all whom it may concern:

Be it known that I, JOSEPH J. WALSER, a citizen of the United States, residing at Chicago, in the county of Cook and State of Illinois, have invented certain new and useful Improvements in Rotary Folding Mechanism for Printing-Presses, of which the following is a specification, reference being had to the accompanying drawings.

10 My invention relates to improvements in rotary folding mechanism for printing presses and particularly to improvements in the mechanism shown and described in Letters Patent of the United States, No. 870,964, to 15 Hans P. Husby, granted November 12, 1907, in which the folding blade in a rotary carrier is operated from normal position into operative position and out of operative position into normal position by two moving guides 20 which, while traveling in the same direction with the folding blade, successively act upon it to move it into and out of operative position; and its object is to provide new and improved mechanism by which the folding 25 blade may be operated without any blow or violent contact of parts, thereby increasing the speed at which the blade may be operated.

In the accompanying drawings:—Figure 1 30 is an end view, showing the folding blade just before it is moved into operative position to fold the paper, being a section on line 1—1 of Fig. 4. Fig. 2 is a section on the same line, showing the folding blade in its 35 folding position. Fig. 3 is an end view showing the folding blade restored to the normal position by the operation of the second moving guide. Fig. 4 is a bottom view of the folding mechanism, with one folding roller 40 removed. Fig. 5 is a detail, being a perspective view of one of the disks showing the engaging stud in dotted lines.

Referring to the drawings:—6 indicates a 45 carrier of a rotary character of any well-known form and description which is mounted in a suitable framework conventionally indicated at 7, and operated in any well-known manner. The rotary carrier is preferably designed to operate also as a cutter to 50 cut the web of paper transversely, by means of a cutting cylinder 9 provided with a knife 10, which coöperates with a cutting groove 11, all of the usual character adapted to sever the web transversely. It is also provided with pins 12 which are shown only

conventionally in the drawings, adapted to engage the paper and to operate in the usual manner.

13—14 indicate folding blades which are carried upon the shafts 15—16 which are 60 journaled in the rotary carrier 6 in the usual manner. The shafts 15—16 are provided at each end with cross-heads or “tumbling-levers” 17 which are fast upon the shafts. The tumbling-levers 17 are provided upon 65 their outer surfaces with rollers 18—19 which are journaled upon suitable pins upon the tumbling-levers and project from the outer surfaces of the tumbling-levers as is best shown in Fig. 4.

70 20—21 indicate circular guides which are carried upon suitable supports, as 22, at each end of the rotary carrier 6 in the same vertical plane as the rollers 18—19, and operate as guides to hold the tumbling-levers and consequently the blades in normal position, that is to say, in inoperative position, which, in the form shown, is substantially at right angles with the radius of the carrier which passes through the center of the 80 tumbling-levers, during the rotation of the rotary carrier, and until it is desired to operate the blades.

23—23 indicate folding rollers of the usual form and operation, which are journaled in 85 the framework below the rotary carrier and are operated in the usual manner. The guides 20—21 are not completely circular, but are cut away at the bottom above the folding rollers to allow for the operation of 90 the rotating cam-members hereinafter described. The openings in the guides 20—21 are staggered with relation to each other at opposite ends of the rotary carrier, as is shown in Fig. 4, and as is shown in solid lines to indicate the ends of the guides in Figs. 1, 2 and 3 at the near end of the rotary carrier and in dotted lines to indicate the ends of the guides at the far end of the carrier, and these 95 openings correspond with the position of the blade-operating disks, one at each end of the rotary carrier, as hereinafter described.

24—25 indicate gears keyed or otherwise secured to the shaft of the rotary carrier.

26—27 indicate gears which are rotatably 105 mounted on studs 28—29 which are suitably secured to the framework 7. The gears 26—27 are adapted to mesh, respectively, with the gears 24—25, and the relations of the gears 24—25 to the gears 26—27 in the 110

form in which my mechanism is shown are the relation of six to one, so that the gears 26—27 will make six revolutions for each revolution of the rotary carrier.

5 30—31 indicate disks which are integral with or secured to the gears 26—27 and are provided upon their inner surfaces with hubs 32—33 which are preferably circular in section.

10 34—35 indicate flanges which project inward from the inner surfaces of the disks 30—31, respectively, forming between their inner surfaces and the outer surfaces of the hubs 32—33 grooves 36—37 which are adapted to receive the rollers 18—19 on the cross-heads 17, to operate them as hereinafter described, the grooves 36—37 being of a width to permit the free passage of the rollers 18—19 through them without any lost motion, as shown in Fig. 5. The stub shafts 28—29 are between the axes of the folding rollers 23 and the rotary carrier, and are located one to one side and the other to the other side of the vertical longitudinal plane 25 of the machine. The disks 30—31 are considerably larger than the gears 26—27 by which they are respectively driven so that the surface speed of the disks may exceed the surface speed of the rotary carrier.

30 It will be obvious from the above description that the two disks 30—31 rotate in the same direction with each other and in the opposite direction to that of the rotary carrier, and the parts are so adjusted and timed in 35 their movement that as the lead end of the tumbling-lever 17 at the farther side of Figs. 1, 2 and 3 passes into the open space at the bottom of the guide 20, the flange 34 upon the disk 30 at the far end of the rotary 40 carrier will engage the roller at the lead end of the cross-head or tumbling-lever, as is best shown in Fig. 1 in dotted lines. As the parts rotate, the disk 30, moving at a greater 45 surface speed than the rotary carrier, will move the groove 36 so that the roller at the lead end of the tumbling-lever will pass through it, causing the lead end of the tumbling-lever, as the carrier rotates, to be moved downward into the position shown in

50 Fig. 2, at which position the paper, which has been carried around by the rotary carrier in the usual manner, is thrust into the bite of the folding rollers 23 and given a transverse fold. The length of the flange 34 is so related to the circumference of the disk 30 and to the speed at which it is driven that by the time that the blade is in the position shown in Fig. 2, the roller at the lead end of the tumbling-lever will have passed completely 55 through the groove 36 and be in position to be disengaged therefrom, as is best shown in Fig. 2. By this time the flange 35 and groove 37 on the roller at the opposite or near end of the carrier will have reached the position 60 shown in Fig. 2, and, traveling at a greater

surface speed than that of the rotary carrier, will engage the roller on the tumbling-lever at the opposite or near end of the rotary carrier, as is also shown in solid lines in Fig. 2. As the disk 31 at this near end of the carrier 70 and the carrier rotate, the groove 37 will engage the roller which has so far been at the lead end of the tumbling-lever upon the near side of the machine, and, causing that roller to pass completely through the groove 37, 75 will move the tumbling-lever and the folding blade with it out of folding position into normal position and thus deliver the tumbling-lever to the guides 20—21 in the position shown in Fig. 3. As was the case with the 80 flange 34 and groove 36, the flange 35 and the groove 37 are so proportioned in length to the circumference of the disk 31 and to its speed of rotation that the engaged roller on the tumbling-lever will be freed from the rear 85 end of the groove as the tumbling-lever again reaches normal position.

It will be obvious from the above description that inasmuch as the disk 30 at the far end of the rotary carrier is traveling in the same direction as the tumbling-lever when it engages it and continues to move in the same direction as the engaged roller on the tumbling lever while moving the blade into folding position, the tumbling-lever and with it 90 the folding blade will be rocked into folding position smoothly and without any blow or violent contact of parts; and it will be also obvious that as the disk 31 upon the opposite end of the carrier at the time of the engagement of the groove 37 with the roller on the end of the tumbling-lever upon the opposite end of the carrier is traveling in the same direction therewith and continues to 95 travel in the same direction therewith during the movement of the blade out of folding position and until the blade is discharged in normal position, the blade will be rocked out of folding position and delivered in normal 100 position smoothly and without any violent 105 contact or blow between the parts. This enables the machine to be run with a speed much greater than where the blade is operated by any such violent contact of parts.

In the drawings I have shown the rotary carrier as carrying two folding blades diametrically opposite each other with the relation to two to one with the cutting cylinder. This is the form in which I prefer to use it, and it will be obvious from the above description that the diametrically opposite blades are alternately operated by the mechanism and operations above described. I have also described the gearing as being so proportioned that the rotary operating disks will be driven six to one with relation to the rotation of the rotary carrier, and this is the form in which I prefer to use it. It will be obvious, however, that a greater relative speed might be used, the parts being propor- 115 120 125 130

tioned accordingly, and I therefore of course do not confine my invention to parts driven at this relative speed.

It will, of course, be understood that a web of paper is delivered in any well-known and approved manner to the rotary carrier, engaged by the pins, and severed crosswise by the cutters at the proper moment of time, also all in the well-known manner. The delivery of the paper is so well understood that it is not shown and the cutters and pins are illustrated only conventionally for the same reason.

What I claim as my invention and desire to secure by Letters Patent is:—

1. The combination with a rotary carrier, a folding blade, and a tumbling-lever at each end of the folding blade, of a rotating member provided with an engaging groove adapted to engage the lead end of one tumbling-lever in its normal position and, while traveling in the same direction therewith, to move said folding blade into operative position, and a second rotating member provided with an engaging groove adapted to engage the lead end of the opposite tumbling-lever in folding position and, while traveling in the same direction therewith, to move said tumbling-lever and folding blade out of folding position and into normal position.

2. The combination with a rotary carrier, a folding blade carried by said rotary carrier, a cross-head at each end of said folding blade, and engaging rollers on said cross-head, of a pair of rotary members located one at each end of said carrier and each provided

with a groove adapted to engage said rollers, and means for driving said rotary members in the same direction with each other and in the opposite direction to that of said carrier, the grooves on said rotary members being respectively adapted to successively engage a roller on said cross-heads at opposite ends of the carrier and, while traveling in the same direction therewith, to successively move said folding blade out of normal position into folding position and out of folding position into normal position.

3. The combination with a rotary carrier, a folding blade carried by said rotary carrier, a cross-head at each end of said folding blade, and engaging rollers on said cross-head, of a pair of rotary members located one at each end of said carrier and each provided with a groove adapted to engage said rollers, means for driving said rotary members in the same direction with each other and in the opposite direction to that of said carrier, the grooves on said rotary members being respectively adapted to successively engage a roller on said cross-heads at opposite ends of the carrier and, while traveling in the same direction therewith, to successively move said cross-heads out of normal position into folding position and out of folding position into normal position, and guides adapted to bear upon said rollers and hold said cross-heads in normal position while not being operated.
